UNITED STATES PATENT OFFICE.

ERNEST C. BOWERS, OF KALAMAZOO, MICHIGAN, ASSIGNOR, BY MESNE ASSIGNMENTS, TO NATIONAL STANDARD COMPANY, OF NILES, MICHIGAN, A CORPORATION OF MICHIGAN.

PAWL-AND-RATCHET MECHANISM.

1,111,128.

Specification of Letters Patent. Patented Sept. 22, 1914.

Application filed December 17, 1912. Serial No. 737,233.

To all whom it may concern:

Be it known that I, ERNEST C. BOWERS, a citizen of the United States, residing at Kalamazoo, Michigan, have invented certain new and useful Improvements in Pawl-and-Ratchet Mechanism, of which the following is a specification.

This invention relates to improvements in pawl and ratchet mechanism.

My improvements are particularly designed for use in railway track drills such as are shown in Patent No. 1,073,322 issued September 16, 1913, on the application of Eugene Cook and this applicant filed October 8, 1912, Ser. No. 724,515, and is a modification and improvement upon the structure there illustrated.

The main objects of this invention are: First, to provide in a pawl and ratchet mechanism, an improved feed mechanism whereby the feed may be varied, which is quickly and easily adjusted and very simple in structure. Second, to provide in a pawl and ratchet mechanism, an improved feed mechanism in which the parts are simple and easily assembled and not likely to become disarranged in use.

Further objects, and objects relating to structural details, will definitely appear from the detailed description to follow.

I accomplish the objects of my invention by the devices and means described in the following specification. The invention is clearly defined and pointed out in the claims.

A structure which is a preferred embodiment of my invention is clearly illustrated in the accompanying drawing forming a part of this specification, in which:

Figure I is a side elevation of a structure embodying the features of my invention, it being shown in operative relation to a rail, no attempt, however, being made to show the rail in its proper proportions. Fig. II is a detail vertical transverse section on a line corresponding to line 2—2 of Fig. I showing details of the feed mechanism.

In the drawing similar reference characters refer to similar parts in both views.

Referring to the drawing, the frame 1 comprises side members and cross members, there being a pair of rear spaced cross members 3. The frame 1 is provided with a base 5. The standard or upright 6 is pivoted at 7 to collapse rearwardly upon the

frame. The standard or upright is held in its erected position by the jointed brace 8. The rail hooks 9 are pivoted to the rearwardly projecting arms on the lower ends of the standard 6 at 10 so that when the standard is erected, stress is put upon the hooks engaged over the rail, as 11. This general arrangement of the frame standard braces and rail engaging hooks forms no part of my present invention.

The tool holder 12 is provided with a chuck 13 for the drill 14. The rear end of the tool holder has a swivel connection, not shown, with the feed screw 16. The feed nut is arranged in the housing 18 on the outer rear cross member 3. The ratchet wheel 19 is provided with a spline 20 engaging the longitudinal groove 21 in the feed screw. The ratchet wheel 19 is arranged between the rear cross members 3. The ratchet wheel is driven through the rock shaft 22 arranged parallel with the tool holder and feed screw. The rock shaft is provided with a rearwardly offset arm 26 on which the pawl 27 is mounted to coact with the ratchet wheel 19. The driving means and connections for the tool holder and rock shaft are not shown or described in detail as suitable means are well known in the art and these features form no part of my present invention.

To vary the feed, the pawl 27 is provided with a control member 34 which is pivoted to the pawl at 35 to coact with the cam 36 on the outer rear cross member 3. The pawl 27 is provided with a stop 37 with which the control member 34 engages as it is raised by the cam 36, thereby holding the pawl out of engagement during a part of its movement when the control member is in operative position, thus securing the slow feed. When the control member is thrown out of operative position as shown by dotted lines in Fig. V, the pawl acts upon the ratchet wheel throughout its full stroke, thus securing the fast feed.

All that is necessary to be done to change the device from the slow and the fast feed is to shift the member 34 from its operative to its inoperative position. The control member is counterweighted so that it is held against the stop 37. When in inoperative position, it is swung over with its weighted end resting on the stop.

My improved feed mechanism is very

simple and economical in structure and very easily and quickly manipulated to change from slow to fast feed or vice versa.

I have illustrated and described my improved feed mechanism in detail in the form in which I have embodied the same in practice. I have not attempted to illustrate or describe various modifications which I contemplate as such modifications or variations 5 in structural details will, I believe, be readily understood by those skilled in the art to which this invention relates. I desire, however, to be understood as claiming my improvements specifically in the form 10 15 illustrated as well as broadly within the scope of the appended claims.

Having thus described my invention, what I claim is new and desire to secure by Letters Patent is:

- 20 1. In a pawl and ratchet mechanism the combination with the frame of a ratchet wheel, a pawl, a rock shaft having an arm on which said pawl is mounted, a member pivotally mounted on said pawl, a stop on 25 said pawl coacting with said member to support it in its operation and constituting a rest to support it in its inoperative position, and a cam on said frame with which said member on said pawl coacts when said member 30 is in operative position to hold the pawl out of engagement with the ratchet during a part of its work stroke and permit it to engage with the ratchet during another part of its work stroke, all coacting for the purpose specified.
- 35 2. In a pawl and ratchet mechanism the combination with the frame of a ratchet wheel, a pawl, a rock shaft having an arm on which said pawl is mounted, a member 40 pivotally mounted on said pawl, a stop on

said pawl coacting with said member, and a cam on said frame with which said member on said pawl coacts when said member is in operative position to hold the pawl out of engagement with the ratchet during a part of its work stroke and permit it to engage with the ratchet during another part of its work stroke, all coacting for the purpose specified.

3. In a pawl and ratchet mechanism, the combination with the frame, of a ratchet wheel, a pawl, a member pivotally mounted on said pawl, a stop on said pawl coacting with said member to support it in its operative position, and a cam on said frame with which said member on said pawl coacts when in operative position to hold the pawl out of engagement with the ratchet during a part of its work stroke and permit it to engage with the ratchet during another part of its work stroke, all coacting for the purpose specified.

4. In a pawl and ratchet mechanism, the combination with the frame, of a ratchet wheel, a reciprocating pawl, a pawl control member mounted on said pawl for adjustment to and from operative position, and a cam on said frame with which said control member when in operative position coacts as the pawl is actuated on its work stroke to hold the pawl out of engagement with the ratchet teeth during a part of its work stroke, all coacting for the purpose specified.

In witness whereof, I have hereunto set my hand and seal in the presence of two witnesses.
